UNITED STATES PATENT OFFICE

139,264

DESIGN FOR A BRUSH FOR DENTURES

John J. Littig, Chicago, Ill.

Application August 4, 1944, Serial No. 114,739

Term of patent 14 years

(Cl. D9—2)

To all whom it may concern:

Be it known that I, John J. Littig, a citizen of the United States, residing at Chicago, in the county of Cook and State Illinois, have invented a new, original, and ornamental Design for Brush for Dentures, of which the following is a specification, reference being had to the accompanying drawing, forming a part thereof.

Figure 1 is a perspective view of a brush for dentures embodying my new design;

Figure 2 is a side elevational view thereof; and Figure 3 is a bottom plan view thereof.

I claim:

The ornamental design for a brush for dentures, as shown.

JOHN J. LITTLIG.
